UNITED STATES PATENT OFFICE.

THOMAS E. MCNEILL, OF NEW YORK, N. Y.

IMPROVEMENT IN SECTIONAL STEAM-BOILERS.

Specification forming part of Letters Patent No. 139,724, dated June 10, 1873; application filed March 30, 1872.

To all whom it may concern:

Be it known that I, THOMAS E. MCNEILL, of the city, county, and State of New York, have invented an Improved Sectional Steam-Boiler, of which the following is a specification:

My invention consists of a sectional steam-boiler, too fully described hereafter to need preliminary description, the main object of my invention being to obtain a thorough circulation of the water in the boiler, a rapid generation of steam without risk of burning out the tubes, and such a disposal of the parts as to obtain an extended heating-surface and a thorough absorption of the heat of the furnace.

In the accompanying drawing, Figure 1, Sheet 1, is a vertical section of my improved steam-boiler; Fig. 2, a plan view of the same, one-half being a section on the line 1 2, Fig. 1; Fig. 3, Sheet 2, a front elevation, partly in section, on the lines 3 4, Fig. 2; Fig. 4, a rear view, partly in section; and, Figs. 5 and 6, detached views drawn to an enlarged scale.

The boiler rests upon and is, with the exception of the end section, contained within a furnace, of which *a* is the base; *b*, the front wall; *c*, the grate-bars; *d*, the bridge-wall; *d'*, a pipe for supplying air; *e e*, the double side walls; *f*, the roof; and *g* the outlet for the products of combustion.

The end sections of the boiler and filling pieces between same close the furnace at the front and back of the same, as will be more fully described hereafter; and the products of combustion, in their upward passage from the fire-place to the chimney, are compelled by partitions *h*, secured to the tubes of the boiler, to take the circuitous course, indicated by the arrows in Fig. 1, around and along the said tubes.

The boiler, or that portion of the same immediately over the fire-place, consists of two sets of inclined wrought-iron tubes of different diameters, one set being arranged directly above the other, and the tubes *A* of the lower set being of greater diameter than the upper tubes *B*; and, in fact, of somewhat greater capacity than the tubes commonly used in boilers of this class. The tubes *A* are not arranged one directly above the other, but are

staggered in the manner plainly shown in Figs. 3 and 4; and the said tubes are closed at their rear ends by caps *D*, more particularly referred to hereafter, and are connected at their front ends to a series of vertical pipes, *E*, of larger diameter than the tubes which communicate at the bottom with a horizontal drum, *F*, cast in sections, as shown in Fig. 3, and supported by the front wall *B* of the furnace. The drum *F* communicates, through an inclined pipe, *G*, of small diameter, with a similar horizontal drum, *H*, placed at a lower level than the said drum *F*, at the rear of the furnace and directly beneath the caps *D* of the lower boiler-tubes *A*. Each of the said caps *D* is composed of two flanged sections, *i* and *i'*, Fig. 5, the former of which is screwed onto the end of its tube, and secured to the latter section by bolts passing through the flanges. The said caps rest one upon the other, and the whole, with the rear ends of the tubes, are supported by a beam, *I*, which is, in turn, supported by the drum *H*, the said beam, with the caps and filling pieces introduced between the latter, forming the rear wall of the furnace. The drum *H* communicates freely with each of the boiler-tubes *A* through a series of vertical wrought-iron pipes, *J*, of small diameter, Figs. 1, 4, and 5, which extend upward from the said drum, and are screwed into tubular projections *i''* formed on each of the caps *D*.

The staggering of the boiler-tubes, and, consequently, of the caps, enables this connection to be readily made without attaching too many tubes to one pipe *J*, and without bringing the connection too closely together, the object of which will be rendered apparent hereafter.

Each boiler-tube *A* is divided longitudinally by a partition, *j*, slipped into the same, and extending almost or quite from one end to the other. (See Figs. 1, 5, and 6.)

The small boiler-tubes *B* of the upper series are, in the present instance, arranged in four parallel rows, indicated by the letters *B*, *B'*, *B''*, and *B'''*.

The tubes *B* and *B'* are connected together at their front ends by couplings *k*, which rest upon the tubes *B''*, and the latter and the tubes *B'''* are connected by similar couplings *k'*, which,

urn, supported by the uppermost. The whole of the tubes B, B¹, B², and communicate, at their rear ends, with transverse drums, L and M, one directly with the other, and supported partly by the walls of the furnace, and partly by the ends of the tubes A. The drum L is divided by a longitudinal partition into two compartments, l and l', and the drum M is similarly divided into compartments m and m'. The compartments l and l' communicate with each other through the tubes B and B¹ and their couplings k, the compartments l' and m' with a short coupling-pipe, n, at one end of the drum, and the compartments m and m' with the tubes B² and B³ and their couplings k'. (See Fig. 1.) Communication is established between the lower compartment of the drum M and the drums F and H at the front and rear of the boiler through a long inclined pipe, P, of small diameter, extending from the furnace directly from the drum M to the drum F, and communicating with the drum F, and communicating with the drum H through the same coupling p, (Fig. 3,) which connection is made with the pipe G, in which all of the boiler-tubes A communicate at their front ends, are of the peculiar pipe best observed in Figs. 2 and 3, each being cast with a smaller pipe, E', at the front communicating with the drum F at the bottom and with the pipe E at the top, for the purpose of facilitating the circulation, as hereinafter described. The said pipes E are also cast with hollow projections x at the sides, as shown in Fig. 3, so that each may receive a considerable number of the tubes A, each of the said pipes being arranged, in the present instance, for attachment to three of the vertical rows of staggered tubes. A steam-drum, L, is secured to the flanged upper end of each of the pipes E, and has suspended within it, by means of a rod, q, one or more concavo-convex perforated plates, r, through which the steam as it rises upward is caused to pass in order to separate the water from the same, and thus prevent priming. The whole of these drums communicate through connecting-tubes with a single transverse drum or drier, R, over which

their couplings k' into the lower compartment m' of the said drum M, and thence through the inclined pipes P and G to the drums F and H; from the latter the water rises in the pipes E E' and J; by which the main boiler-tubes A are filled from both ends. The large pipes E, however, are relied upon to fill the tubes A, the smaller pipes J being merely supplementary feeders, arranged to supply the tubes at their lower ends, and thus prevent the emptying and burning out of the same owing to the rapid generation of steam. The partitions j in each of the said tubes A also induce a return circulation and aid in preventing the water from being forced out of the same when steam is rapidly generated, for when the water in the lower portion of one of the tubes beneath the partition is heated, it will with the steam blow upward toward the front end of the said tube, and enter and rise in one of the pipes E; but there will also be a return eddy or circulation in the said tube above the partition j, as indicated by the arrows in Fig. 1. This return circulation from the tube and pipe E, with the water which is continually entering the lower end of the said tube from its pipe J, will effectually prevent the forcing out of the water and the consequent burning of the tube, for the more rapid the generation of steam, and the greater the tendency to drive the water out, the more rapid will be this circulation, and the greater the quantity of water supplied by the supplementary feeder J. Pipes J, communicating with a water-supply, are essentially different from the circulating pipes hitherto arranged at the lower ends of inclined boiler-tubes, and merely connecting the same, inasmuch as in the latter case the rapid generation of steam will drive the water from the tubes as effectually as if the connecting-pipes were not employed.

There will be an upward circulation in the pipes E of the heated water entering the latter from the several tubes A, and a return circulation from the said pipes through the pipes E' to the drum F, from which the water will again rise into the pipes E. The hot water from the drum F, however, will not pass through the pipe G to the drum H, and thus interfere with the above-described circulation in the tubes A, as the connection with the

cost for the whole number of tubes of both series will not be greater than that of an uniform set of ordinary size. Owing to the tubes at the bottom of the boiler being of such large diameter, the conversion of the entire body of water therein into steam, and the consequent burning of the tubes, which frequently ensues when small tubes are employed, cannot take place, while the smaller tubes at the top of the boiler where the gases are not so hot as nearer the fire present a larger heating-surface in proportion to the water they contain, which, therefore, is more rapidly heated than in tubes of larger diameter arranged in a like position. The tubes B, of the upper series, although constituting part of the boiler and in direct and continuous communication therewith, form, with the drums L and M, a feed-water heater for absorbing the heat from the products of combustion after the latter have passed upward around the tubes A, and before they reach the chimney g. As the whole number of tubes B of the upper series are disconnected from any permanent part of the boiler at their front ends, they can contract and expand freely, but any movement caused by the contraction or expansion of the lower tubes A must take place at their rear ends. Such movement is permitted by the caps D, which can slide freely one over the other, and by the supplementary feed-pipes J, which, being of wrought-iron of small diameter, and being connected to the caps at comparatively long intervals, owing to the staggering of the tubes, have sufficient elasticity to yield to the movements caused by contraction and expansion. It will be seen that pipes J, connected to a stationary part of the boiler only at their lower ends, and to the lowest set of tubes at some distance above these stationary ends, will yield freely throughout their length, while in boilers in which rear connecting-pipes have hitherto been used such pipes have been so secured at both ends to stationary parts of the

boiler as to be incapable of accommodating themselves to the movements of any but the central tubes.

I claim as my invention—

1. A sectional boiler consisting of two sets of communicating tubes, one above the other, and the lower being of larger diameter than the upper, all substantially as specified.
2. The combination, substantially as described, of the partitioned drums L and M with the upper tubes B of the boiler.
3. The combination, substantially as described, of the upper tubes B, and their connecting-drums, forming a feed-water heater, with the distributing-drum F.
4. The combination, with the tubes A, of feed-pipes E, communicating with the upper ends of the said tubes, and of supplemental feed-pipes J, of smaller diameter than the pipes E, communicating with the lower ends of the said tubes, all substantially as and for the purpose specified.
5. The combination, with the said tubes A, of yielding or elastic feed-pipes J, substantially as described.
6. The combination, with the tubes A and pipes J, of caps D, cast in two sections, adapted to each other and to the said tubes and pipes, substantially as described.
7. The combination of the tubes A, connecting-pipes J, and drum H communicating with the pipes J, substantially as described.
8. The pipes E, each cast in one piece, with a return-pipe, E', of smaller diameter.
9. The combination of the drum-section F with the pipe E and return-pipe E', substantially as and for the purpose described.

In testimony whereof I have signed my name to this specification in the presence of two subscribing witnesses.

THOS. E. McNEILL.
